UNITED STATES PATENT OFFICE.

JAMES P. BALL, OF PHILADELPHIA, PENNSYLVANIA, ASSIGNOR TO THE KEYSTONE SAFETY NUT LOCK COMPANY.

DESIGN FOR A BOOK-MARK.

SPECIFICATION forming part of Design No. 16,896, dated September 14, 1886.

Application filed June 10, 1886. Serial No. 204,808. Term of patent 14 years.

To all whom it may concern:

Be it known that I, JAMES P. BALL, a citizen of the United States, residing in the city and county of Philadelphia, State of Pennsylvania, have invented and produced a new and original Design for Book-Markers, of which the following is a specification, reference being had to the accompanying drawing, forming part thereof.

10 The leading feature of my design for a book-marker is a tongue of the form of a cross with a body of the form of a heart.

A represents the body of a book-marker, the same being of the form of a heart. Within 15 the body is a tongue, B, which is of the form of a cross. About the place of junction of the body and tongue is a crown, C, and on the top of the vertical limb of the cross is the representation of a dove, D, with an olive-branch.

20 On the body, on each side of the lower limb of the cross, are fields E, on the face of each of which is a halo.

I claim—

1. A design for a book-marker having a body of the form of a heart and a tongue of 25 the form of a cross, with a crown thereon, the said tongue and crown being within the outlines of the heart, as shown and described.

2. A design for a book-marker having a body of the form of a heart, a tongue of the 30 form of a cross, a crown, and the representation of a dove with an olive-branch on the tongue, as shown and described.

3. A design for a book-mark having a body of the form of a heart, a tongue of the form 35 of a cross, a crown, and a field, with a halo on each side of the lower limb of the cross, all as shown and described.
